United States Patent Office

Des. 221,966
Patented Sept. 21, 1971

221,966

TOY GUN

James L. Howe, Temperance, Mich.
(7485 Apache Trail, Toledo, Ohio 43612)

Filed Apr. 1, 1970, Ser. No. 22,167

Term of patent 14 years

Int. Cl. D21—02

U.S. Cl. D34—15

FIG. 1 is a top view of the toy gun of my new design;
FIG. 2 is a view in elevation;

FIG. 3 is an end view, as seen from the muzzle end;

FIG. 4 is an end view, as seen from the handle or grip
end;

FIG. 5 is a cross-sectional view of the handle or grip,
taken along line 5—5 of FIG. 2;

FIG. 6 is a bottom view; and

FIG. 7 is a view in perspective.

I claim:

The ornamental design for a toy gun, as shown.
